DESIGN FOR A PLUG RECEPTACLE ESCUTCHEON PLATE

James D. McDonald, Los Angeles, Calif.

Application July 19, 1947, Serial No. 140,388

Term of patent 14 years

(Cl. D26—13)

To all whom it may concern:

Be it known that I, James D. McDonald, a citizen of the United States, residing at Los Angeles, county of Los Angeles, State of California, have invented a new, original, and ornamental Design for a Plug Receptacle Escutcheon Plate, of which the following is a specification, reference being had to the accompanying drawings, forming part thereof.

Fig. 1 is a front elevation of a plug receptacle escutcheon plate showing my new design.

Fig. 2 is a view in end elevation thereof.

I claim:

The ornamental design for a plug receptacle escutcheon plate, substantially as shown.

JAMES D. McDONALD.
